UNITED STATES PATENT OFFICE.

JOSEPH PARTAIN, OF WILLIAMS, CALIFORNIA.

PUMP.

1,326,777.

Specification of Letters Patent. Patented Dec. 30, 1919.

Application filed May 12, 1919. Serial No. 296,470.

To all whom it may concern:

Be it known that I, JOSEPH PARTAIN, a citizen of the United States, residing at Williams, in the county of Colusa and State of California, have invented new and useful Improvements in Pumps, of which the following is a specification.

This invention relates to pumps of the force type, and aims to provide a pump 10 which will deliver a large and even flow of water with a small amount of power.

An object of the invention is to provide a pump having a plurality of pistons alternately operating within a single cylinder, so 15 that the water is forced upward in a constant and even stream.

Another object is to arrange the connecting rods of the pistons so that an even force will be exerted thereon, thereby reducing the 20 power necessary for the operation of the pump.

A further object is the provision of a novel form of piston, which is especially adapted for a pump of this character, the construction being such as to deliver a maximum quantity of water and to prevent the least resistance to the water passing through the cylinder upon the return stroke of the piston.

Other objects and advantages of the invention will appear as the following description is read in connection with the accompanying drawings.

In the drawings:

Figure 1 is an elevation of a pump constructed in accordance with the present invention, the pump, cylinder and casing being shown in section.

Fig. 2 is a transverse sectional view on the line 2—2 of Fig. 1.

Fig. 3 is an enlarged central sectional view through the cylinder and piston illustrating the construction of the said pistons and the arrangement of the rods.

Fig. 4 is an enlarged detail vertical section 45 through one of the pistons, the sections being at right angles to Fig. 3.

Fig. 5 is an enlarged view of the connections between the operating and plunger rod of the piston.

Fig. 6 is a fragmentary perspective view 50 of the connection between the bail and piston.

Figs. 7 and 8 are detail perspective views of the valve members.

Referring more specifically to the drawings, like characters of reference denote cor-

responding parts throughout the several views.

As shown in the accompanying drawings, the pump comprises a cylinder 10, which is 60 connected to the lower end of the casing 7 through the medium of threads 12 or other suitable connection. The casing extends upward and is provided with a spout 11 for the discharge of the water or other liquid 65 lifted by the pump.

Operated within the cylinder 10 is a plurality of pistons, preferably three in number, which are designated by the numerals 14, 15 and 16. These pistons are designed to 70 be alternately operated within the cylinder 10 in a manner to be hereinafter described, the said cylinder being of sufficient length to permit of an alternate reciprocatory motion of the piston. 75

These pistons are of novel construction and comprise a frame 17 and valve members 18, the former comprising an outer ring 19 and an inner ring 20 of relatively less width. The inner ring 20 is of less diameter than 80 the outer ring and clamped between these two rings is a packing 21, preferably of leather. This packing extends downward upon the inside of the outer ring 19 and upward upon the outside of the ring for contact with the cylinder 10. As before stated the inner ring 20 is of less width than the outer ring 19 and the upper edge of the first mentioned ring and the upper edge of the packing 21 is disposed below the upper edge 85 of the outer ring 19, so as to provide a seat 22. 90

Mounted within the frame 17 are a pair of semi-circular valve members 18, these valve members being each provided with pintles 23 mounted within openings 24 provided upon diametrically opposite sides of the ring 19. The edges of the valve members 18 rest upon the seat 22 when in closed position and within the outer ring 19, so that upon the upward stroke of the piston 100 the valves are closed and the water or other fluid is lifted. The inner or meeting edges of the valve members 18 are straight and are ground to form a tight joint, as indicated at 95 25, the upper corners being rounded so as to 105 permit of the pivotal movement of the valve.

Secured to each of the valves is a bail 26, the lower ends of which are riveted to the inside of the outer ring 19 as indicated at 27, the extremities of the bails being bent inward and seated within notches 28 formed in the upper edge of the inner ring 20 and 110

packing 21, so as to provide a smooth surface for the seat 22. The ends of the bail are also provided with openings 29 which register with the openings 24 in the outer 5 ring 19, the pintles 23 of the valve members 18 passing through these openings. Each of the pistons has secured to one of the valve members 18, a coiled spring 30, so that when the said members are opened the 10 spring will contact with the opposite valve member and aid the valve in turning to the seats 22 under pressure of the water or other liquid being pumped.

Connected to the bail 26 of the lower piston 15 is a rod 31. Surrounding the rod 31 is a tubular rod 32, the lower end of which is connected to the bail 26 of the piston 15, while surrounding the rod 22 is another tubular rod 33 having its lower end connected to the bail 26 of the piston 14. The rods 20 are thus concentrically arranged within the cylinder and are connected to their respective pistons in a manner to exert an even pull thereon. The upper ends of the rods 25 31, 32 and 33 are connected respectively to the lower ends of rods 34, 35 and 36, the two last mentioned rods being offset at their point of connection, while the rods 31 and 34 are in alinement. The upper ends of the 30 rods 34, 35 and 36 are connected respectively to the cranks 37, 38 and 39 of a crank shaft 40, the said cranks being disposed at different angles so that one of the pistons is always upon the upper working stroke. The 35 shaft 40 is mounted in suitable bearings 41 supported in any desired manner and has secured upon one end a pulley 42 by means of which power is applied to the shaft 40.

From the foregoing description and accompanying drawings, it will be seen that the invention provides an exceedingly efficient pump especially adapted for irrigating purposes and that it will deliver evenly a large volume of water at the expense of a minimum amount of power.

Having thus described my invention what is claimed is:—

1. The combination with a cylinder of a piston comprising a frame formed of con-

centrically disposed rings of different widths 50 to provide a valve seat entirely surrounding the interior of the frame, semi-circular valves pivotally mounted within the frame and adapted to rest upon the seat and entirely fill the space within the frame and 55 capable of opening to provide an unobstructed passage to said frame and a packing clamped between said rings and extending upward around the outer ring.

2. A piston comprising a frame formed 60 of concentrically disposed rings of different widths to provide a valve casing entirely surrounding the interior of the frame, a packing clamped between the rings and having one edge flush with the valve seat, semi-circular valves pivotally mounted within the frame and adapted to rest upon the seat and entirely fill the space within the frame and capable of opening to provide an unobstructed 65 passage to said frame and a bail having its ends connected at diametrically opposite sides of the frame.

3. A piston comprising a frame formed of concentrically disposed rings of different widths to provide a valve seat and entirely 75 surrounding the interior of the frame, semi-circular valves pivotally mounted within the frame and adapted to rest upon the seat and entirely fill the space within the frame and capable of opening to provide an unobstructed 80 passage through said frame and resilient means carried by the piston for aiding the valve members to return to closed position.

4. A piston comprising a frame formed of 85 concentrically disposed rings of different widths to provide a valve seat entirely surrounding the interior of the frame, semi-circular valves pivotally mounted within the frame and adapted to rest upon the seat and 90 entirely fill the space within the frame and capable of opening to provide an unobstructed passage to the frame with a coil spring mounted upon one valve member for contact with the opposite member to aid said members in returning to closed position.

In testimony whereof I affix my signature.
JOSEPH PARTAIN.
